UNITED STATES PATENT OFFICE.

GEORGE E. HIEBER, OF CINCINNATI, OHIO, ASSIGNOR TO THE CONCRETE SURFACING MACHINERY COMPANY, OF CINCINNATI, OHIO, A CORPORATION OF OHIO.

POWER HAMMER.

Application filed March 20, 1925. Serial No. 16,962.

This invention relates to that type of manually manipulated power hammers which are operated by means of flexible rotating shafts, and its object is to provide a portable structure of this character wherein the blows of the hammer are cushioned by means of a body of air confined within a reciprocating cylinder and the force which pulls the hammer back from the chisel or other tool upon which it is operating is also exerted through a cushion of air.

In the accompanying drawing, Fig. 1 is a vertical section of this improved hammer on the line 1—1 of Fig. 2. Figs. 2, 3 and 4 are sections on the lines 2—2, 3—3 and 4—4 respectively of Fig. 1.

Similar reference letters refer to like parts throughout the several views.

The body 1 of this hammer is formed with a handle 2 of any desired character by which it can be positioned relative to the work. Its opposite end 3 is tubular to receive the reciprocating cylinder 4, and its end is closed by means of the plug 5 which serves as a guide for the tool A.

The cylinder 4 is fitted with a head 5 having a central hole to receive the stem 6 of the piston 7. This stem is formed with a small groove 8 to permit the passage of air into the outer end of the cylinder. The end of this stem is adapted to contact with the inner end of the tool A, which is slidable in the plug 5.

A vertical shaft 11, mounted in the rear end of the body 1 and in the closure plate 12, carries a pinion 13, and its lower end may be drilled at 14 and tapped to receive the end of a connector 15 which attaches to any desirable flexible shaft 16 by means of which this device may be driven.

The main crank comprises the disks 17 and 18, united by a crank pin 19, preferably formed on one of the disks and extending through a hole in the other. Shafts 21 and 22 are formed integral with the disks 17 and 18 respectively and bushings 23 and 24 constitute bearings therefor; the former being mounted in the body 1 and the latter in the closure 12. The disk 18 is formed with teeth 50 to mesh with the teeth of the pinion 13.

The crank pin 19 extends through the eye 25 at the inner end of the connecting rod 26. The cylinder 4 is formed to receive the bushings 27 in which the pin 28 is mounted and this pin extends through and is non-rotat-

table in the eye 29 at the outer end of the connecting rod 26. This pin may be hollow if desired.

As shown in Figs. 1, 3 and 4, the cylinder 4 and the bushings 27 are formed with air passages 31 and the pin 28 is formed with ports 32 which align with the passages 31 when the crank pin is about midway of its backward stroke. That is, these ports are out of alignment while the cylinder 4 is moving outward, or to the left in Figs. 1 and 2, and during the beginning and during the ending of the inner movement of the cylinder. At the inner and outer ends of these movements the ports and passages are as shown in Fig. 4, that is, the passages to the interior of the cylinder 4 are closed. The crank shafts are supposed to turn clock-wise in the drawings.

The operation is as follows: When the ports 32 and passages 31 are aligned at the middle of the back stroke of the crank, air may rush into the cylinder 4, permitting the hammer 7 to lag and slide to the outer end of the cylinder 4.

The small groove 8 permits the air at the front end of the cylinder to escape very slowly so that the hammer is cushioned at the front end of the cylinders. When therefore the crank reaches the rear end of its stroke, the hammer 7 will be at the outer end of the cylinder and the space at the inner end of the cylinder will be filled with air which is compressed to some extent by the hammer as the cylinder moves outward. This air cannot escape as the ports 32 and passages 31 are no longer in alignment. The result is that when the stem 6 strikes the tool A, the blow is cushioned by the air in the inner end of the cylinder and the impact of the hammer 7 on the tool is "alive" and is similar to the blow delivered by the pistons of the well known pneumatic hammers.

This air cushion not only secures the very desirable "live" blows of the hammer but it also relieves the actuating parts of the very destructive shocks which would be received if this hammer 7 were rigid with the cylinder 4. This therefore insures long life to this tool.

If no leakage occurred, this tool could be assembled with the desired amount of air within the rear end of the cylinder 4, but as this air is liable to leak out, I provide means

for recharging this air chamber at each stroke of the hammer so as to insure a proper and sufficient cushion at each end at all times. The details of construction and the proportions of the parts may all be changed by those skilled in the art without departing from the spirit of my invention as set forth in the following claims.

I claim:—

- 10 1. In a power hammer, the combination of a body, a cylinder slidable therein, a crank-shaft mounted in said body, a connecting rod extending therefrom to the cylinder to move the cylinder inwardly and outwardly, a piston-hammer in said cylinder, a pin connecting the cylinder to the connecting rod, said pin and cylinder being formed with air passages which align while the cylinder is making the middle portion of its inward stroke and are out of alignment during the remainder of the time to cause the piston hammer to be cushioned during the outward movement of the cylinder.
- 15 2. In a power hammer, the combination of a body, a cylinder slidable therein, a crankshaft mounted in said body, a connecting rod extending therefrom to move the cylinder inwardly and outwardly, a piston-hammer in said cylinder, said cylinder being formed with a passage to admit outside air to its inner end, and means controlled by said connecting rod to open said passage during the inward stroke of the cylinder and to close it during the outward stroke, said air serving to cushion the piston-hammer during said outward stroke.
- 20 3. In a tool of the class described, the combination of a body, a cylinder slidable therein, a crank shaft mounted in said body, a connecting rod extending from the crank shaft to said cylinder, a pin connecting the connecting rod and cylinder, said cylinder having an air passage adapted to admit outside air to its inner end, said pin extending across the passage and provided with an air port adapted to align with said passage at a predetermined point of its inward strokes, said port and passage being out of alignment during the outward stroke of the piston, a piston-hammer in said cylinder, and having a stem extending from the cylinder in the opposite direction to said pin, an annular closure for the end of the cylinder from which the stem extends, said hammer being cushioned by the air within the ends of the cylinder.

4. In a tool of the class described, the combination of a body, a cylinder slidable therein, a crank shaft mounted in said body, a connecting rod extending from the crank shaft to said cylinder, a pin connecting the connecting rod and cylinder, said cylinder having an air passage extending to its interior, said pin extending across the passage and provided with an air port adapted to align with said passage at a predetermined point of its stroke, a piston-hammer in said cylinder, and having a stem extending from the cylinder in the opposite direction to said pin, an annular closure for the end of the cylinder from which the stem extends, said hammer being cushioned by the air within the ends of the cylinder the air being admitted to one end through said air port and passage, said stem having a longitudinal groove to admit air to the other end of the cylinder.

5. In a tool of the class described, the combination of a body and a crank revolvable therein, a crank pin on the crank, a connecting rod mounted on the pin, a hollow member slidable in said body and operatively connected to said rod, and a hammer mounted in said hollow member, the parts being formed with air passages connecting to the outside air to secure air cushions for said hammer within the hollow body, the passage to the inner end of the cylinder being opened and closed by said connecting rod.

6. In a power hammer, the combination of a body, a cylinder slidable therein, a crankshaft mounted in said body, a connecting rod extending therefrom to move the cylinder inwardly and outwardly, a piston-hammer in said cylinder, said cylinder being formed with a passage controlled by the angular position of said connecting rod to admit outside air to its inner end, and means to open said passage during the inward stroke of the cylinder and to close it during the outward stroke, said air serving to cushion the piston-hammer during said outward stroke, said piston-hammer having a longitudinally grooved stem extending outwardly from the cylinder, and said cylinder having an annular closure for the outer end of the cylinder and through which said stem extends, the groove in the stem permitting a restricted flow of air into and out of the outer end of the cylinder at all times.

GEORGE E. HIEBER.
